UNITED STATES PATENT OFFICE.

BLAINE H. HARRIS, OF ST. PAUL, MINNESOTA, ASSIGNOR TO BROWN & BIGELOW, OF ST. PAUL, MINNESOTA, A CORPORATION OF MINNESOTA.

LOOSE-LEAF MEMORANDUM-PAD-BOX CONSTRUCTION.

Application filed January 19, 1925. Serial No. 3,448.

My invention relates to loose leaf memorandum pad box construction wherein it is desired to provide a box of such a construction as can be made up and carried in stock 5 ready to be shipped upon short notice to the customer.

A feature of the invention resides in providing a box having side walls and a bottom portion together with a cover which extends 10 over a portion of the top of the box and provided with means for holding the corners and side walls of the end of the box where the cover of the box is secured in a simple and inexpensive manner.

15 It is also a feature of this invention to provide a box for loose leaf memorandum sheets which can be held so that they can be picked up and used as memorandum and wherein the construction is such so that the portion that 20 forms a partial cover of the box may be stamped out flat and while in this flat state can be printed upon with an advertisement or other display matter and thus permit the manufacture of the boxes in their entirely 25 together with the cover portion, excepting that the cover is not printed upon until the order is received from the customer.

It is very important in the advertising business to provide an article of the nature as described 30 in this invention so that it can be delivered as soon after the order has been received as possible, and to do this it is necessary to have a stock of the boxes all made up, excepting that the cover members are not 35 printed with the advertisement.

It is also very important that an article of this kind must be made very reasonable in price, as in the advertising business these articles are given away by the purchaser with 40 their advertising thereon. To facilitate this I have provided the customer with a box put together in a manner so that the same means which holds the cover intact with the box is sufficient, with the construction of the cover, 45 to form a connecting means for one end of the box.

In the drawings forming a part of this specification

Figure 1 is a perspective view of my box 50 as it would appear in finished form.

Figure 2 is a longitudinal section of the same.

Figure 3 is a longitudinal section similar 55 to Figure 2 before the cover has been attached thereto.

Figure 4 is the blank formation of the cover.

Figure 5 illustrates the cover in finished form, ready to be attached to the box.

In the drawings the memorandum box A 60 is formed with a bottom 10 and side walls 11 and front end 12 and rear end 13.

The box A is formed of sheet metal or other suitable thin material and is stamped out of the flat sheets and then formed up so as to 65 provide the upright side walls 11, 12 and 13.

The front wall 12 is formed with a central opening 14 to permit the loose memorandum sheets 15 to be easily engaged and lifted, one at a time, out of the memorandum pad box, 70 thus providing a loose leaf memorandum pad for a desk with sheets that can be easily picked up and used for memorandum purposes.

The front wall 12 is formed with ears 16 75 which are folded onto the sides 11 and held by the rivet or eyelets 17 so as to securely support the corner of the box and to provide a finished appearance.

The rear wall 13 of the box A is bent upward to lie adjacent the ends of the walls 11 and is secured firmly in place by means of the downwardly depending flange 18 formed on the cover 19.

The cover 19 is made of sheet material and is stamped out in the flat state as illustrated in Figure 4. These covers are kept in this shape until they are printed upon with suitable advertising matter as directed by the customer purchasing these memorandum 85 boxes and then the covers are formed up with the flange 18 depending as illustrated in Figures 1, 2 and 5. The cover 19 is provided with side flanges 20 from which project the ears 21 which are secured by the eyelets 22 so as to hold the cover firmly fixed to the side walls 11. A front downwardly depending flange 23 is formed on the cover 19 which provides a finished construction to the front edge of the cover and also forms a 90 stiffening means which strengthens the cover and prevents the same from being bent out of shape.

The box A, together with the cover 19, is preferably made of a sheet material which 105 has been coated to simulate wood or other suitable material and thus when it is stamped out it provides a very attractive desk memorandum pad. The construction of the cover, which includes the supporting means for the 110

rear wall 13, is very important in my invention by reason of the fact that it provides a box which is economical to make and yet gives a finished appearance to the article when completed.

This construction is also important for the reason that the boxes can be entirely finished excepting as to the flanges 18, 20 and 23, and thus the advertisement can be printed onto the flat formation of the cover 19, which is a very desirable feature.

In accordance with the patent statutes I have described the principles of operation of my memorandum box and while I have illustrated a particular construction in the drawings I desire to have it understood that this is only illustrative and that the invention can be carried out by other means and applied to uses other than those above set forth, within the scope of the following claims:

1. A memorandum pad box including a bottom, side and end walls, a cover, depending flanges extending from said cover, one of said flanges engaging the end wall of said box to hold the same against the side walls, and the oppositely disposed depending flange of said cover forming an inwardly depending stiffening edge adapted to extend between the side walls.

2. A memorandum box construction, including a cover adapted to be secured to the side walls of the memorandum box, depending flanges formed on the four sides of the cover, one of said flanges forming an engaging means to support and hold one end of the memorandum box firmly in position and another forming a stiffening edge extending between the sides of said box.

3. A memorandum box including a body portion having a bottom, side and end walls, a cover having depending ears which are adapted to be rigidly secured to said side walls and a back flange on said cover adapted with said ears to form a lock for holding the end and side walls of said box rigidly in place.

4. A cover for a memorandum box adapted to hold a series of loose memorandum sheets including a member A adapted to be rigidly secured to said box, said member having parallel extending flanges, one of which is adapted to engage the back wall of the box to hold it in place, and the other of which is adapted to provide a stiffening rib along one edge of the cover, and a spacing member between the sides of the box.

BLAINE H. HARRIS.
